Attorney

UNITED STATES PATENT OFFICE.

HORACE E. GILMORE, OF SPRING HILL, KANSAS, ASSIGNOR OF ONE-HALF
TO JOHN S. MACKEY, OF SAME PLACE.

SASH-LOCK.

SPECIFICATION forming part of Letters Patent No. 320,551, dated June 23, 1885.

Application filed April 27, 1885. (No model.)

To all whom it may concern:

Be it known that I, HORACE E. GILMORE, a citizen of the United States, residing at Spring Hill, in the county of Johnson and State of Kansas, have invented certain new and useful Improvements in Sash-Locks; and I do hereby declare that the following is a full, clear, and exact description of the same, reference being had to the annexed drawings, 10 making a part of this specification, and to the letters and figures of reference marked thereon.

Figure 1 of the drawings is a sectional side elevation of a window-frame and sashes embodying my invention; Fig. 2, a perspective view of one of the casings and spring-bolts; Fig. 3, a sectional view thereof; Fig. 4, a horizontal section taken through one of the casings, to show the form of the bolt; and Fig. 5 20 is a detail view of the bolt.

The present invention has relation to that class of sash fasteners or locks in which a ratchet rod or bar is connected to the top of the window-frame and extends down to the top of the lower sash, and latches or other like devices connected to each of the sashes operate in connection with the ratchets on the rod or bar to hold the sashes either opened or closed, as found desirable.

30 The object of the invention is to improve the construction of the above-mentioned class of sash fasteners or locks; and it consists in the details of construction substantially as shown in the drawings, and hereinafter described and claimed.

In the accompanying drawings, A represents the window-frame, and B C the upper and lower sashes, respectively.

To the top of the frame A is suitably connected one end of a rod, D, provided along its length with a series of ratchet-teeth, a.

Near the lower end of the rod D are two or more square notches, b, and a like notch at the top of the rod, as shown in dotted lines.

45 The blocks or casings which contain the

bolts (shown at E) are provided with suitable eye-plates, c, for attaching them to the tops of the sashes by screws or other similar fastenings. The casings E have a central hole, d, through which the rod D extends, so as to allow the sashes to move up and down. The casings E contain the bolts F, which are of peculiar construction, having a U-shaped end, e, entering and passing through two perforations, f, in the inner side or end of the casing. 55

The outer or opposite end of the bolt F is provided with a thumb-piece, g, and a coil-spring encircles the bolt at this end and bears against the thumb-piece and casing. Bending the bolt F at its end, as shown at e, greatly strengthens it where most required, and the perforations f give a double bearing, thus rendering the bolt more readily operated, with less liability to twist or bend out of its normal position or shape. 65

The notches b in the rod D are for the purpose of locking the sashes when closed, while the ratchets a will admit of the sashes being raised, but not lowered, without pressing on the thumb-piece g of the bolt F, to disengage it with the ratchets. 70

Having now fully described my invention, what I claim as new, and desire to secure by Letters Patent, is—

In a window-sash lock, a vertical rod having ratchets and notches at its upper and lower ends and connected to the window-frame, in combination with suitable blocks or casings connected to the sashes and having central holes for the rod and containing a spring-bolt, 75 said bolt at its inner end being U-shaped and passing through double perforations in the casing, for the purpose set forth. 80

In testimony that I claim the above I have hereunto subscribed my name in the presence of two witnesses.

HORACE E. GILMORE.
